UNITED STATES PATENT OFFICE.

HANS L. ORG., OF NEW YORK, N. Y.

CARPENTER'S PLANE.

Application filed January 26, 1927. Serial No. 163,687.

This invention relates in general to carpenters' planes, and more particularly to carpenters' planes for planing vertically extending surfaces such as the edges of flooring and the like.

Among the objects of the present invention it is aimed to provide an improved carpenter's plane in which the cutting edges of the blades do not project from the supporting surface of the plane but project from the edges of the tool to form a plane that is particularly adapted for use with flooring.

To this end the present invention aims to provide an improved blade carrier comprising an open frame having openings extending through the body of the frame to reduce the weight of the frame to a minimum and to reduce the supporting surface to a minimum, thereby in turn to reduce the friction to a minimum.

Among other objects of the invention it is aimed to provide an improved handle for a plane of this character adapted to be supported by the two hands of the operator, which handle is arched to conform to the natural position of the hands and thus protect the wrists of the operator from undue strain.

Among other objects it is also aimed to provide an improved means for anchoring the cutting blades in place on a plane of this character. To the latter end, it is a specific object of the present invention to provide blade receiving grooves in the frame of the tool, anchoring plates having tail pieces to engage the blades, and a screw having a beveled neck to cooperate with the anchoring plates to jam or wedge the tail piece into engagement with the blade and thus lock it in position on the frame.

The present invention still further aims to provide deflecting lips or plates for receiving the chips or shavings as they are cut by the blade and deflecting them upward and outward both out of engagement with the work and the cutting blade.

These and other features, capabilities and advantages of the present invention will appear from the subjoined detail description of one specific embodiment thereof illustrated in the accompanying drawings, in which

Figure 1 is a side elevation of the tool;
Fig. 2 is a plan of the tool with portions thereof broken away;
Fig. 3 is an end elevation of the tool;

Fig. 4 is a section on the line 4—4 of Fig. 2;
Fig. 5 is a section on the line 5—5 of Fig. 4;
Fig. 6 is a section on the line 6—6 of Fig. 2.

The tool consists essentially of a main frame portion 1 having a guide piece 2 and a handle 3 attached thereto. The main frame, as indicated in Fig. 2, has openings 4 formed therein whereby the weight of such frame is reduced to a minimum and the surface 5 reduced to a minimum, in turn to minimize the friction created by the surface 5 during operation of the tool without impairing the efficiency thereof. The handle 3, as particularly illustrated in Fig. 1, has two grip portions 6, 6 which are arched relative to the tool to receive the two hands of the operator so that the tool can be operated by the two hands of the operator and protect the wrists of the operator from undue strain.

The present tool is particularly adapted for use in laying flooring such as parquet flooring, in which the blade 7 projecting from the edge 8 of the tool is used for cutting the tongue portion of the flooring or outer edge 80 of the flooring, and the blade 9 of the edge 10 spaced from the surface 5 of the tool is used for cutting the groove of the flooring.

The frame member 1, as illustrated in Fig. 2, is preferably provided with two parallel slots 11 and 12 to receive the cutting blades 7 and 9, as illustrated, with their cutting edges projecting from the edges 8 and 10 respectively.

Means for locking the blades 7 and 9 in place on the frame 1 will now be described. Two locking plates 13 and 14 are provided. The locking plate 13 has a tail piece 15 and an orifice 16, which orifice 16 has a beveled surface to receive the beveled neck 17 and serve as a cam to cooperate with the beveled neck 17 of the screw 18. The screw 18 has a shank portion 19 engaging the threaded orifice 20 of the frame 1 and a head 21 registering with the orifice 22 of the second plate 23.

The locking plate 14, similar to the locking plate 13, is provided with a tail piece to engage the blade 9 and the orifice 24 which has a beveled surface to engage the beveled neck of the screw 25, the screw 25, similar to the screw 18, engaging a threaded orifice in the frame 1 and having its head engaged in an orifice formed in the second plate 23. The second plate 23 is provided with two additional orifices to receive the screws 26 and 27 which enter orifices formed in the frame 1 and thus anchor the second plate 23 to the

frame 1 and incidentally thereby form a guide to aline the blades 7 and 9 in place. The screws 18 and 25 cooperate with the locking plates 13 and 14 and the second plate 23 to anchor the blades 7 and 9 in place, see particularly Fig. 4 where the screw 18 is shown with its beveled neck 17 engaging the beveled surface of the orifice 16 with the locking plate 13 to wedge the tail piece 15 against the blade 7 and securely anchor the blade 7 between the tail piece 15 and the frame 1.

With this arrangement, the blades 7 and 9 may be secured in place when projecting a greater or less extent as desired. The screw 18 or 25, depending upon the blade to be adjusted, is turned to release the locking plate in engagement therewith to relieve the blade, whereupon the blade can be adjusted and the screw again turned home to anchor the locking plate in place without removing the second plate 23. The second plate aforesaid serves not only to aline both blades in their respective slots and thereby in proper position for cutting, but by engaging the upper surfaces of the locking plates also serves to maintain such locking plates in proper position for engaging the cutting blades.

With planes of this character, especially for use in laying flooring, difficulty has been encountered in removing the chips and shavings out of engagement with the blades and the path of movement of the bearing surface 5. To this end, the present invention provides deflecting surfaces. For the blade 7 the deflecting surface 28 inclines upwardly from the bearing surface 5 and continues into the flaring surface 29 of the pocket adjacent to the blade 7. The flaring surface 29 continues around into engagement with the side of the blade 7. From the foregoing, it will be seen that as chips are formed by the blade 7, they will be deflected away from the blade 7 by the flaring surface 29, and if they engage the deflecting surface 28 they will be deflected upwardly and out of the path of movement of the bearing surface 5. The blade 9 is provided with a deflecting surface 30 similar to the deflecting surface 28 at the bottom of the pocket formed adjacent to the cutting blade 9 similarly to deflect upwardly any chips that might engage such surface and therefore deflect them out of the path of movement of the supporting surface 5. Similarly, the surface 31 adjacent to the surface 30, will deflect outwardly away from the blade 9 any chips that might pass to it.

It is obvious that various changes and modifications may be made to the details of construction without departing from the general spirit of the invention as set forth in the appended claims.

I claim:

1. In a device of the class described, the combination with a frame having a supporting surface, a cutting blade secured to said

frame with its cutting edge projecting from the edge of said frame to cut surfaces extending at an angle to the supporting surface of said frame, there being a pocket in said frame disposed adjacent to the cutting blade, and a deflector plate having an upper surface inclining upwardly from the supporting surface to deflect the chips or shavings upwardly, the frame having a deflecting lip with its outer surface curving away from the cutting blade to form one wall of said pocket and serving to deflect the chips or shavings away from said blade.

2. In a device of the class described, the combination with a frame having a supporting surface, of a slot formed in said frame, a cutting blade disposed in said slot with its cutting edge extending from the edge of said frame to cut a surface extending at an angle to said supporting surface, a locking plate having a tail piece engaging the side of said blade, and a screw for securing said locking plate to said frame and frictionally holding said blade in place.

3. In a device of the class described, the combination with a frame having a supporting surface, of a cutting blade, there being a slot in said frame to receive said cutting blade to permit its cutting edge to extend from the edge of said frame to cut a surface at an angle to said supporting surface, there being a groove in the upper surface of said frame, a locking plate positioned in said groove and having a tail piece extending into engagement with the side of said blade, there being orifices in said locking plate and frame, said locking plate having a cam face in its orifice, the orifice in said frame being internally threaded, and a screw having a beveled head engaging the threaded orifice of said frame with its beveled head cooperating with the cam face of said locking plate to wedge the cutting blade between said tail piece and frame thereby to securely anchor it in place.

4. In a device of the class described, the combination with a frame having a supporting surface, of a cutting blade, there being a slot in said frame to receive said cutting blade with its cutting edge extending from the edge of said frame to cut a surface extending at an angle to said supporting surface, there being a groove in said frame, a locking plate disposed in said groove and having a tail piece engaging said blade, an orifice provided with a cam face, there being an internally threaded orifice in said frame registering with the orifice in said locking plate, a second plate provided with an orifice, means for anchoring said second plate on said frame with its orifice registering with the threaded orifice in said frame, and a screw having an enlarged head and a beveled neck adjacent thereto, the threaded portion of said screw engaging the threaded orifice of said frame, the enlarged head engaging the orifice in said

second plate and the beveled neck engaging the cam face of said locking plate whereby the screw will cooperate with said frame, second plate and locking plate frictionally to hold the blade between said tail piece and frame against displacement during operation of the tool.

5. In a device of the class described, the combination with a frame having a supporting surface, of two cutting blades, there being parallel slots in said frame inclining to the horizontal edges of said frame to receive

the cutting blades to permit their cutting edges to extend from the horizontal edges of the frame to cut surfaces disposed at angles 15 to said supporting surface, locking plates engaging said cutting blades, a second plate between which and the frame said locking plates are positioned, and screws cooperating with said second plate, locking plate and frame 20 frictionally to anchor said cutting blades against displacement in said frame during operation of the tool.
